UNITED STATES PATENT OFFICE.

LEVI McMILLAN, OF WILMINGTON, NORTH CAROLINA.

ADDRESSING-MACHINE.

1,150,784.

Specification of Letters Patent. Patented Aug. 17, 1915.

Application filed August 22, 1914. Serial No. 253,185.

To all whom it may concern:

Be it known that I, LEVI McMILLAN, a citizen of the United States, residing at Wilmington, in the county of New Hanover and State of North Carolina, have invented 5 certain new and useful Improvements in Addressing-Machines, of which the following is a specification.

An object of my invention is to provide a 10 machine which is so constructed that catalogues, magazines, letters, circular letters, cards or like publications to be addressed and to be sent to a compiled mailing list can be placed in quantities in a common receptacle and will be taken separately from the receptacle, carried to a point where the name is imprinted thereon and will then be discharged from the machine.

A further object is to arrange the carrying and printing mechanism in such coöperative relation that the printing mechanism is operated only during the necessary intervals to accomplish the printing action.

A still further object is to provide a label 25 applying mechanism in a relation to attach a label to the publication prior to the printing action at the point at which the address is to be placed.

Another object is to construct the feeding, 30 label appliance, and printing mechanisms in such a manner that the parts thereof can be adjusted to use various mailing lists, to treat labels of various characters and to act upon publications of a large or small size with 35 equal facility.

Yet another object is to so construct and arrange the several parts of the mechanism that the operation thereof is automatic and the parts come into operative relation in the 40 proper intervals without manual adjustment or manipulation.

With other objects in view, which will be referred to, my invention consists in the peculiar combination and novel arrangement 45 of parts, such as will be hereinafter more fully described in connection with the accompanying drawings and more particularly pointed out in the appended claims.

In the drawings: Figure 1 is a view in 50 side elevation of my improved mechanism with parts shown in section. Fig. 2 is a longitudinal vertical sectional view through the machine. Fig. 3 is a view in top plan of the structure disclosed in Figs. 1 and 2. Fig. 4 is a transverse vertical sectional view 55 taken on the line 4—4 of Fig. 2 looking in

the direction of the arrow. Fig. 5 is a fragmentary sectional view taken on the line 5—5 of Fig. 2. Fig. 6 is a view in perspective of the roll by which the labels are severed from the main label strip preparatory to the attachment to the publication. Fig. 7 is an enlarged fragmentary perspective view to better illustrate the structure of the severing knife. Fig. 8 is a view in perspective of a section of the name stamp carrying tape. Fig. 9 is a view in perspective to illustrate the coöperative placing of the rolls adapted to feed the tape for each printing operation. Fig. 10 is a side elevation of the mechanism 60 adapted to stop the feed of the name stamp carrying tape prior to the printing action. Fig. 11 is a view in perspective of the roll by which the glue or other adhesive material is applied to the labels. Fig. 12 is a fragmentary perspective view of a portion of the label strips with a severed label illustrated as turned face down to show the application of the adhesive thereto. Fig. 13 is a detail elevation of the stop for the label 65 feed mechanism. Fig. 14 is a view in top plan of the receptacle in which the publications are placed to be fed to the operating mechanism. Fig. 15 is a view in front elevation of the disclosure in Fig. 14, with portions of the structure illustrated in section. Fig. 16 is a transverse sectional view taken vertically through the receptacle as illustrated in Figs. 14 and 15.

My invention embodies a machine which 70 is so constructed that any desired publication, as for instance a catalogue, magazine, cards, or other subject matter of a like nature of which a great number are to be addressed and are to have the name of a 75 compiled mailing list imprinted thereon may be placed in a common receptacle in a considerable quantity and will be taken separately from the receptacle, carried over a table and pass a mechanism which affixes 80 a label thereto, and then have the carrying movement continued to a point adjacent a printing mechanism where the address is affixed, the carrying movement then being 85 continued until the subject-matter being 90 printed upon is moved from the end of the table and is then discharged into a mail bag or other suitable receptacle, or it might be 95 discharged to a mechanism by which the publication, a predetermined number at a 100 time would be banded or wrapped in packages for ready handling.

Also it is a purpose of my invention that the labels may be fed to the operating mechanism in a continuous length or strip and that the means by which the name stamps 5 are carried can be applied and removed from the machine as a whole to permit the application of other mailing lists and further to so arrange the several parts that an adjustment thereof may be made to accommodate 10 various subject matters to be treated and at the same time the automatic operation is not interfered with.

To accomplish the purpose as is hereinbefore set forth, my machine consists of the 15 frame which comprises a base 1 having a superstructure or frame 2 mounted thereon. A power shaft 3 is mounted transversely across the frame 2 in suitable bearings provided at one end thereof and a belt 20 pulley 4 is carried by the power shaft 3 to receive driving motion from any suitable source, not shown. A shaft 5 is journaled at the opposite end of the frame 2 from the disposition of the shaft 3 to extend in a line 25 parallel therewith and to be preferably in the same horizontal plane. A sprocket wheel 6 is secured on the power shaft and a sprocket chain 7 passes over this sprocket wheel and over a wheel 8 mounted on the 30 shaft 5, and an arcuated track 9 is disposed beneath the upper extent of the sprocket chain 7 to give this chain a slight rise from the wheel 8 to sprocket wheel 6, the rotation of the drive pulley 4 being as indicated by 35 the arrow in Fig. 1 and the direction of movement of the chain also in a clockwise direction in the disclosure in Fig. 1.

A table 10 is positioned between the side members of the frame 2 and this table, as 40 better illustrated in Figs. 4 and 5, is made to be adjustable, a hinge connection 11 being provided between the members 10 and 12 of the table and the yoke members 13 and 14 mounted to be capable of vertical adjustment 45 to raise and lower the two members of the table. These yoke members 13 and 14 each have a stem 15 formed as a part thereof to extend downwardly to a point adjacent the base member 1, the adjusting levers 50 16 and 17 are pivoted near their centers on base member 1 and at their one end have a pivotal connection with the stem 15 of the yokes 13 and 14, respectively. The screw-threaded bolt members 18 and 19 are connected with the free ends of these adjusting 55 levers and extended up through the floor of the base member 1 to pass through the brackets 20 and 21, and the hand wheels 22 and 23 are swiveled to these brackets 20 and 60 21 and have screw threaded orifices through the centers thereof in which the bolts 18 and 19 are received and which parts are so arranged that the turning of the hand wheels 22 and 23 in the one direction or the other 65 causes an extension of the bolts 18 and 19

therefrom or a retraction thereto thus causing the adjusting levers 16 and 17 to be swung around their points of pivotal connection on the floor of the base member 1 and in consequence causing the table top 70 members 10 and 12 to be raised or lowered as the screw bolt members 18 and 19 may be extended or retracted.

Guideways 24 and 25 are provided longitudinally through the table members 10 and 12 adjacent the edges thereof and to extend parallel to each other and to the side members of the frame 2 and the conveyer chains 26 and 27 are received to work in these guide ways, the sprocket wheels 28 and 29 being provided on the power shaft 3 to cause a carrying motion of the conveyer chains and the wheels 30 and 31 mounted on the shaft 5 to have the conveyer chains passed thereover and to support the chains 85 at the feed end of the machine.

A hopper or receptacle 32 is mounted at the feed end of the machine on the frame 2 and adjacent the point at which the shaft 5 is mounted and this hopper 32 is made of the proper dimension to receive the booklets or other publications which are indicated at 33 and to embrace these publications sufficiently closely that they will be centrally spaced from side to side with respect to the 95 conveyer chains 26 and 27. As these conveyer chains 26 and 27 are mounted over the sprocket wheels 28 and 29 secured directly on the power shaft 3, a constant motion is transmitted thereto and stops 34 are 100 provided on certain of the links of each of these conveyer chains to engage with the lowermost publication contained within the hopper 32 and move this publication over the table and through the machine to the 105 discharge end where the publication is discharged from the machine over the power shaft 3 and over the sprocket wheels 28 and 29. As the stops or lugs 34 are carried by 110 certain of the links of the conveyer chain, the distance at which these stops are placed apart may be varied and adjusted to fit the requirements of use and operate upon publications of various sizes by shifting the links in their disposition along the lengths 115 of the chain, and thus the conveyer may be adjusted to take large or small publications or to advance or retard the time at which the publications are taken from the receptacle.

By the mechanism as hereinbefore described, the publication may be placed in the receptacle or hopper 32 in a considerable number, stacked one upon the other, and as each of the stops or lugs 34 of the conveyer 125 chains 26 and 27 comes into engagement with one of the publications contained within the hopper this publication will be taken from the forward end of the receptacle 32 and will be moved over the table member 10 and 130

from this member onto the table member 12, the adjustable feature of these two members 10 and 12 being to accommodate publications of various thicknesses. The bracket members 35 are secured to the side members of the frame 2 and these bracket members are branched out to form two arms as better illustrated in Figs. 1 and 2, each of these arms having a bearing 36 provided at the upper end thereof. The spindle shafts 37 and 38 are mounted across the brackets 35 within the bearing 36 on the arms thereof and the bearings 36 are so formed that these spindle shafts may be readily mounted and removed.

The name stamps are made in the form of the usual rubber stamp as better illustrated in Fig. 8 and these name stamps 39 are to be attached to a carrying tape 40 and when compiled upon this tape will be mounted and at predetermined spaced points apart. A storage reel 41 is provided to have the tape 40 wound thereon and to be fitted on the spindle shaft 37 carried by the brackets 35 and a winding reel 42 is provided to be received on the spindle shaft 38 to turn therewith, a groove pulley 43 being mounted on this spindle shaft 38 and connected to receive power from the drive shaft 3 by a belt 44 which is mounted over a pulley 45 secured on the shaft 3.

As the publications are carried over the table 12 above which the printing is done only in a spaced apart relation, it is preferable that an intermittent movement be transmitted to the tape 40 to bring the name stamps 39 into the proper relation for the printing action and thus it is possible to place these name stamps upon the tape in a much closer relation than would otherwise be possible. A tape propelling or carrying roll 46 is mounted across the bracket member 35 on a shaft 47 and this roll 46 has the sprocket teeth 48 positioned around the periphery thereof at points spaced apart on the longitudinal extent of the roll to be adjacent the side edges of the tape 40 in its passage over this roll, the tape having the edges thereof perforated as at 49 to receive the sprocket teeth 48 and the idler roll 50 is mounted to maintain the tape in the proper relation upon the carrying roll 46 being provided with orifices therein to receive the ends of the sprocket teeth as they project through the perforations provided in the tape. An ink roll 51 is mounted across the brackets 35 to extend parallel with the spindle shaft 37 and to be in proximity thereto, a pressure roll 52 being provided to have the tape 40 passed therearound and to cause the name stamps 39 secured on this tape to come to a bearing relation against the ink roll 51 as the tape is carried forward by the turning movement of the carrying wheel 46, an ink fount 53 being provided at

suitable points to supply ink to the roll 51. A bearing roll 54 is revolvably mounted beneath the table section 12 and this roll is connected to be adjusted upwardly and downwardly with the movement of the table 78 to permit a regulation of the pressure exerted against the name stamps to accomplish the printing action, a printing roll 55 which is cut away to provide bearing faces at opposite points thereon being mounted at a point directly above the bearing roll 54 to have the tape 40 passed thereover and this printing roll 55 is of such a size that in its revolution the name stamps 39 will come to a position over the bearing faces provided 80 upon the roll and will be carried down to cause the imprint against the publication passing the bearing roll 54 by which the pressure exerted upon the type of the name stamps is attained and maintained. 85

It is preferable that an intermittent movement be transmitted to the carrying roll 46 to carry the tape 40 forward the required distance prior to printing action and in consequence it is necessary that a like movement be imparted to the printing roll 55. To accomplish this purpose, the gear wheel 56 is mounted on the shaft 57 by which the printing roll 55 is carried and this gear wheel 56 meshes with a gear 58 mounted to 95 revolve with the carrying roll 46. Certain of the links of the sprocket chain 7 have teeth 59 provided on the outer faces thereof and due to the engagement of said chain in its upper extent with the arcuated track 9, 100 a rack-like structure is provided as the chain passes beneath the gear wheel 56 and the engagement of the teeth 59 with the teeth of this gear wheel causes the printing roll 55 to be turned. Through the meshing of the gear wheel 58 with the gear 56 a rotary motion is transmitted to the carrying wheel 46 and the tape is wound from the reel 41 past the ink roll 51 where ink is applied to the type of the name stamps 39. 110 The stamps are engaged on the reverse side by the bearing faces of the printing roll 55 and are brought into contact with the subject-matter to be printed upon and which is held in the proper relation by bearing roll 54. In this way the address is printed and the tape is carried forward until the links of the chain 7 having the teeth 59 formed thereon have passed the location of the gear wheel 56 and are out of mesh therewith. To 115 accomplish a better carrying action it is preferable that a gear 60 be mounted on the shaft by which the roll 50 is carried to engage with the teeth of the gear wheel 58 and thus this roll 50 will be turned positively. 120

It is preferable that the operation of the parts of the printing mechanism be stopped immediately the printing action has been accomplished and the printing roll 55 has assumed the position illustrated in Fig. 2 139

where it is in a relation to accomplish the next subsequent printing action, and to accomplish this end a stop mechanism as better illustrated in Fig. 10 is provided. 5 This stop mechanism comprises a disk 61 which is secured on the shaft 57 to revolve with the gear wheel carried thereby and this disk 61 has the notches 62 provided at diametrically opposite points thereon. A 10 dog member 63 is pivoted at 64 to the bracket 35 and a spring 65 is provided to normally hold this dog in a relation that the engaging end thereof is in a relation to fit within the notches or slots 63 of the disk 15 61. As it is necessary that the printing roll 55 make but a half revolution to accomplish the printing action, and due to the fact that the carrying roll 46 is of a diameter equal to the diameter of the working portion of 20 the printing roll 55 this wheel likewise requires but a half revolution to accomplish a successful action and therefore the rotation of the shaft 57 may be stopped with each half revolution or when the dog 63 will normally engage within the notches 62, however, when the next subsequent printing action is to take place this dog must be released from its engagement against the tension of the spring 65 and to accomplish this 25 object, an arm 66 carried by the dog 63 adjacent the pivot thereof has a pinion 67 mounted on the lower end thereof to be engaged by the teeth 59 of the rack links of the sprocket chain 7 and this engagement 30 causes movement of the dog from a locked position and permits rotation of the shaft 57 as the rack teeth 59 come into engagement with the gear wheel mounted thereon. It will be understood that the pinion 67 will 35 pass from the rack portions of the sprocket chain before this portion has completed its driving action upon the shaft 57 and thus the dog 63 is in the proper relation to engage with one of the notches 62 immediately 40 the rack teeth 59 are out of the operative relation and the stoppage of the movement of the printing mechanism is positive and immediate. The rack teeth, as is stated hereinbefore, are carried by certain of the 45 links of the chain 7, and when it is desired to adjust the printing mechanism to be operated in a varied interval with respect to the carrying mechanism or the conveying mechanism, the links having the teeth 59 50 formed thereon are mounted at a point in advance or in the rear of that shown in Fig. 1 of the drawing and in this way the engagement with the wheel 56 and also with the wheel 67 will be advanced or retarded 55 and in consequence the printing mechanism will be brought into operation and will be stopped at a varied interval.

The connection to the spindle shaft 38 through the belt 44 running over the belt wheel 45 on the power shaft 3 over a belt

wheel 43 on this spindle shaft 38, causes the spindle shaft to be constantly driven, and as the feed of the tape wound onto the reel 42 carried by this spindle shaft 38 is intermittent to follow the movement of the carrying wheel 46, it is essential that some means be provided to permit a stoppage of rotation of the spindle shaft 38 and also to cause a rotation thereof during the feeding action of the tape through the turning movement of the carrying wheel. To accomplish this purpose the belt 44 is made of the round or cord type to be received over grooved belt wheels and is mounted rather loosely around the pulleys 43 and 45 so that as the carrying roll is in the stopped position and the tape 40 has been wound onto the reel through that length which has been loosened by the last carrying action, the belt 44 will slip around the belt pulley 43 and the spindle shaft 38 will be permitted to stand still while the rotation of the power shaft 3 is yet continued. To adjust the parts to secure the right tension and degree of tightness of the belt 44, a belt 90 tightener 68 is provided to work upon the belt adjacent the passage thereof over the belt pulley 43 and to permit regulation of the parts to accommodate various operating conditions. 95

With the mechanism as hereinbefore described, addresses from a compiled mailing list may be printed on any desired publication which can be placed in the hopper or receptacle 32 and fed forward by the conveyor chains 26 and 27 and a very efficient action will be obtained. However, it is desirable in certain classes of addressing that a label be affixed to the subject matter to be addressed and that the name be printed upon this label and I have therefore provided a label affixing mechanism which works cooperatively with the parts of the mechanism as hereinbefore set forth to apply and secure a label to the subject-matter 100 to be addressed prior to the printing of the name and address thereon and which is so arranged that the labels are taken from a continuous strip and after having an adhesive applied thereto are affixed at the desired point in a manner to obviate possibility of the adhesive oozing or being pressed from around the edges of the label and thus causing subsequent publications 105 placed upon the label face of said publications sticking and becoming accidentally secured one with the other. 110

A frame 69 is provided to carry the label affixing mechanism and this frame 69 is constructed to be fitted on the frame 2 at a 115 point between the disposition of the receptacle or hopper 32 from which the publications or other subject-matter to be addressed are taken and the printing roll 55 where the address is imprinted thereon, 120 125 130

the perforated lugs 70 and 71 being provided on the frames 69 and 2, respectively, to be held in the proper relation by a clamp bolt 72. A spindle 73 is mounted upon the 5 upper portion of the frame 69 to be capable of turning movement and to also be detachable and this spindle 73 has the reel 74 having the label strip 75 wound thereon mounted in a relation to be capable of turning 10 movement. An inclined label carrying table 76 is provided between the side members of the frame 69 and the feed rolls 77 and 78 are mounted in a pair to have the tangential faces thereof slightly disposed above the 15 top of the table 76. At a point along the extent of the table 76, the severing rolls 79 and 80 are disposed, the one roll, as better illustrated in Figs. 6 and 7 being provided with a serrated knife 81 and the bearing 20 roll 80 having a groove 82 in which this serrated cutting knife works, thus as the label strip 75 is carried forward between the rolls 77 and 78, it will be passed over the table top and between the severing rolls 25 79 and 80 where the strip is cut into the rectangular labels 83 as is illustrated in Fig. 12. At a point further along the extent of the inclined table 76, the feed rolls 84 and 85 are disposed to carry forward the individual labels 83 as cut from the label strip 30 75 and these feed rolls 84 and 85 pass the individual labels to the glue rolls 86 and 87, the structure of which is better illustrated in perspective in Fig. 11. These glue rolls 35 comprise the pressure roll 86 and the glue roll proper 87 and these rolls at the ends have bearing portions 88 and 89 provided to contact and to hold the rolls properly spaced apart and to also engage the edges 40 of the individual labels 83 and carry these labels therebetween in the proper relation. The rolls 86 and 87 are cut away on their one side for a distance of perhaps one third the circumference and the roll 87 is mounted 45 in a glue pan 90 to receive a supply of adhesive therefrom and to have the surplus adhesive wiped therefrom by a wiper 91 disposed at the proper point to accomplish the most efficient action. By reason of the 50 fact that the roll 87 is, in its body portion, made of somewhat less extent than the superficial extent of the roll and also the transverse extent of the label strip, and by reason of the fact that approximately one-third of the circumference thereof is cut away, the glue or adhesive taken by this 55 glue roll 87 will be applied to the label 83 only through the center portion as is illustrated in Fig. 12 and then when the label 60 is subsequently affixed and pressure is exerted thereon to secure the proper adhesion the glue will not ooze or be pressed from beneath the edges of the label.

A drive gear 92 is mounted to be engaged by and mesh with the teeth 59 pro-

vided on the rack links of the sprocket chain 7 as these racks or links pass adjacent thereto and an intergearing is established between the several rolls mounted as a part of the label affixing mechanism so that these rolls 70 will all be revolved in a direction to carry the label strip and the individual labels cut therefrom in the proper course over the table 76. It will be understood that at the same time that the teeth 59 are engaged with 75 the drive gear 92 a publication is being carried forward by the conveyer chains 26 and 27 and suitable guides 93 are provided to direct the individual labels with the adhesive applied thereto in a downward path 80 from the rolls 86 and 87 to a position against the upper face of the publication 33 which is being carried over the table member 10 and a pressure roll 94 which, as illustrated in Fig. 1 may have the pressure spring 95 85 mounted to secure the proper pressure, is positioned to bear against the labels and smooth this label upon the publication as the conveyer chains 26 and 27 move forward and the publication is carried along the table 90 member 10.

To secure the proper operation of the label affixing mechanism it is essential that the glue roll 87 makes one complete revolution and to bring the parts to a positive stop 95 after the accomplishment of the desired movement, a stop mechanism is applied to the gear wheel 92, which stop comprises a disk 96 affixed to turn with the gear wheel 92 and having a single notch 97 spaced at 100 the proper point around its periphery. A dog member 98 is pivoted at 99 and a spring 100 holds this dog 98 normally in a relation to engage in the notch 97 when the engaging end of the dog and this notch come into registry, a pinion 101 being provided on an arm 102 carried by the dog 98 to engage with the rack teeth 59 and thus raise the dog from the engaged relation against the tension of the spring prior to the commencement of the turning of the gear wheel 92 through the mesh of the teeth 59 therewith.

It is the purpose that the receptacle 32 in which the publications are placed shall in each adaptation of the machine be adjusted 110 to just the right size to hold the publications properly stacked and yet to permit the withdrawal of the bottommost and to allow the remainder of the publications to fall a distance equal to the distance of the publications withdrawn. The structure of this receptacle is better illustrated in Figs. 14, 15 and 16 and this structure comprises a framework 103 which may be mounted and held 115 on the main frame 2 in any approved manner. This framework 103 has the guideway or slot 104 formed in one of the bottom members thereof to extend in a direction from front to back of the framework, and 120 similar guide slots are provided in the bot-

3
 tom members at the ends of the receptacle to be preferably in alinement and to extend in a direction transversely of the machine. The standards 106 and 107 each have a bearing foot and the clamp bolts 108 are received through the base feet and through the slots or guideways 104 and 105 and thus the standards are mounted in a relation to permit an adjustment of the confining walls 5 within which the booklets, magazines, form letters, cards or other like publications are received and held in the proper spaced relation.

Under certain circumstances, as for instance when placing the address upon form letters, and in other connections where the sheet or publication to be addressed is thin, it will not be possible to depend upon the stops 34 to take the publications from the 10 container, for the reason that a sufficiently fine adjustment cannot be obtained to take a single sheet of paper or a single card. In such connections the conveyer links carrying the projections or stops 34 are 15 displaced by plain links and a feed roll 109 is mounted in the lower portion of the framework 103 to project in its upper extent slightly above the floor of the receptacle and thus be in a position that as the 20 roll is turned a feeding action of the lowermost sheet contained within the receptacle is accomplished. An adjustable front 110 is mounted on a stem 111 which has a slot 112 therethrough to be received over a clamp 25 bolt 113 mounted on the framework of the machine. The provision of this adjustment allows the front to be moved and held in the proper relation, it being desirable that this front 110 be positioned a distance above 30 the floor of the receptacle and above the roll 109 that but a single publication will be permitted to pass from the receptacle upon each feeding action. A strip or fingers 114 of rubber or a like material are carried by the lower edge of the adjustable clutch in a position to exert a holding pressure against a second sheet, card, or publication if carried by the lowermost publication 35 fed from the receptacle by the movement of the roll 109 or by the engagement of the stops carried by the conveyer chain and in a manner that the forward movement will be stopped and will not be completed until the next interval in which a publication 40 is to be discharged onto the conveyer chain.

While the foregoing description has set forth the feeding roll 109 as a part of the structure, it will be understood that in some 45 connections this roll can be dispensed with and an efficient operation of the machine will yet be obtained, in such instances, it being my purpose to entirely remove the roll 109 from the receptacle and to lower the

receptacle from the main frame 2 to a position that the stops on the conveyer chains 26 and 27 will engage with one of the publications within the receptacle and carry this publication to a point to discharge upon the conveyer chains and upon the table members 10. As the feed roll 109 is in operation, power to cause a proper turning thereof at the necessary predetermined intervals is derived through a gear wheel 115 mounted on the shaft by which the roll 109 is 50 journaled and meshing with a gear wheel 116 which is positioned on the main frame 2 or at any other suitable point to have the teeth 59 of the chain 7 mesh therewith, and thus the operation of the feed roll 109 is 55 only during the passage of the rack teeth 59 on the chain 7 adjacent thereto and during the mesh of these teeth with the teeth of the gear wheel 115 and in this way the publications are taken from the receptacle 60 32 and are deposited on the table top members 10 to be taken by the conveyer chains 26 and 27 prior to each label-affixing and printing operation.

The operation of the machine is as follows:—A number of publications 33 or other subject matter to have the address imprinted thereon are stacked in the hopper or receptacle 32 to be one upon the other and power is transmitted to the power shaft 3 through 65 a proper connection with the drive pulley 4, the conveyer chains 26 and 27 are carried along in a path from the feed end of the machine to the discharge end and as the stops 34 engage with the publication this 70 publication is moved forward, at the same time the label-affixing mechanism has been placed in operation and the label strip has been extended from the reel 74 a sufficient distance and severed by the serrated knife 108 75 to form one of the individual labels 83, the adhesive applying mechanism is also brought into operation and as the publication passes beneath the guide 93 the label is deposited thereon and the continued travel 80 of the conveyer causes the publication to be carried beneath the pressure or smoothing roll 94 where the label has the necessary pressure exerted thereon to secure the proper adhesion. The rack teeth 59 engage with the 85 pinion 67 and the dog 63 is moved from the engagement in the notch 62 of the disk 61, thus when the teeth 59 mesh with the gear wheel mounted on the shaft 57 the printing roll 55 is turned and in a like manner revoluble movement is transmitted to the carrying roll 46 and the name stamp carrying tape 40 is moved forward the proper distance to carry the name stamp then having 90 its back disposed against one of the bearing faces of the printing roll 55 to a relation that the stamp imprints the name and address upon the label affixed to the publica- 95 100 105 110 115 120 125

tion, it being of course understood that ink is applied to the main stamp as it passes between the ink roll 51 and the pressure roll 52. Immediately the teeth 59 forming these racks 5 pass from the power wheel 92 and from the wheel mounted on the shaft 57, the stop mechanism of these two parts will come into operation and a positive holding of the parts is accomplished so that the mechanism is in 10 the proper relation for the next subsequent labeling and printing action and the continued movement of the conveyer chains 26 and 27 carry the publication now labeled and addressed, over the table member 12 15 and the publication is discharged at the lower end of the machine over the power shaft 3 where it may be received in a mail bag or other suitable receptacle, or if desired a conveyer mechanism might be disposed to 20 receive the publications as discharged from the table member 12 and these publications can thus be moved to any desired point or carried to a mechanism to accomplish a further handling thereof. As the chain 7 is 25 constantly driven, the spaced-apart racks provided thereon will come successively into mesh with the gear wheel 116 by which the feed mechanism from the receptacle 32 is operated and it is thus insured that a publication is placed for each of the subsequent 30 printing operations or labeling and printing operations. The adjustment of the table members 10 and 12 permits the accommodation of the machine to label and 35 address publications of various thicknesses and by varying the size of the receptacle 32 still greater latitude in the subject-matter treated can be secured, also it will be evident that variation in the disposition of the stops 40 34 located along the length of the conveyer chains 26 and 27 and also in the positioning of the rack links carrying the teeth can be made to accommodate various operating 45 conditions.

From the foregoing it will be seen that I have provided an addressing machine which is so constructed and has the parts thereof so arranged that booklets, magazines, cards and other like publications may have the 50 addresses printed thereon from a compiled mailing list, the parts being so arranged that a number of the booklets or other subject matter are placed in a common receptacle and will be taken separately therefrom, carried 55 to a point where a label is affixed thereto and then carried forward farther where the name and address are imprinted upon the labels, the forward movement being continued still further until the publication is 60 discharged from the machine. Further it will be obvious that by slight variation in the setting of the parts of this mechanism the machine can be adapted to accommodate various forms of publications and publica-

tions of a variety of sizes, and at the same 65 time the compiled mailing lists may be changed by the placing of other compiled lists in the form of name stamp carrying tape and in all connections the operation and successful working of the machine is 70 automatic and is constant without the necessity of manual manipulation.

While I have herein shown and described one specific form of my invention it will be understood that slight changes might be 75 made in the form and arrangement of the several parts as hereinbefore set forth without departing from the spirit and scope of my invention, and hence, I do not wish to be limited thereto except for such limitations 80 as the claims may import.

I claim:—

1. An addressing machine comprising means to take the publications singly, means to be brought into operation to imprint the 85 address upon the publications as taken, stops carried by the means to take the publications and mounted in a manner to permit adjustment of the relative positioning thereof to adapt the same to operate upon publications 90 of various sizes, means to bring the printing mechanism to a stop subsequent to the one printing action and prior to the next successive action, adjustable means to operate said printing mechanism and to also control 95 the operation of the stop mechanism, and power means to drive the machine through successive operations.
2. An addressing machine comprising a receptacle in which publications are placed 100 in quantities, means to take the publications singly from the receptacle, means to apply a label to each of said publications, said means by which the publications are taken comprising a conveyer arranged to operate 105 with publications of various sizes and thicknesses and to carry the same through the machine in a relation to have the label affixed at any desired points, means to imprint an address upon the label as affixed to the publication, power means to maintain the movement of the conveying mechanism constant, and mechanism arranged to derive movement from the operation of said conveying 110 mechanism to bring the label applying and printing mechanism into operation at the proper intervals.
3. An addressing machine comprising a frame, a conveyer means to take the publications singly and carry these publications 120 through the machine, means to imprint the address upon the publications in their path through the machine, means to adjust the conveyer means to operate upon publications of various sizes and thicknesses and to carry 125 the same through the machine in a path to have the address imprinted at any desired location upon the publications, power means

to, maintain the operation of the conveyer constant, and driving means for said printing mechanism so arranged that driving power is transmitted from the power means 5 at the proper intervals.

4. An addressing machine comprising a supporting frame, conveyer chains mounted on said frame, to take the publications singly and to carry these publications through the 10 machine, printing mechanism to imprint the address upon the publications in their travel through the machine, means carried by certain of the links of the conveyer chains to engage the publications as taken and to hold 15 the same in the passage through the machine and said links connected in the chains in a manner that they may be adjusted along the length of the chains to act upon publications of various sizes and to carry the publications through the machine in a path to have the address printed thereon at any desired point, and power means to maintain the operation of the conveyer constant and to automatically bring the printing mechanism 20 into operation in the proper intervals and in successive operations.

5. An addressing machine comprising a supporting frame, a receptacle mounted on the frame in which publications are placed 30 in quantities, conveyer chains mounted on the frame, means carried by the links of said conveyer chain, to take the publications singly from the receptacle and said links so connected in the chains that they may be disposed at any point along the length of 35 said chains to act upon the publications of various sizes, means carried by the frame to affix a label to each of said publications, and printing mechanism to imprint the address 40 upon said labels.

6. An addressing machine, comprising a supporting frame, a receptacle mounted on the frame in which publications are placed in quantities, conveyer chains mounted on 45 the frame to take the publications singly from the receptacle, means carried by the frame to affix a label to each of said publications, printing mechanism to imprint the address upon said labels, means carried by 50 certain of the links of said conveyer chains to engage with the publications and take the same from the receptacle and said links so connected in the chain that the same may be adjusted along the length of the chain to be 55 properly spaced to act upon publications of various sizes and to permit carrying of the publications through the machine to have the label affixed at any desired point, and power means to automatically carry the machine 60 through successive operations.

7. An addressing machine comprising a frame, a receptacle carried by said frame in which publications are placed in quantities, conveyer chains mounted on the frame 65 to take the publications singly from the re-

ceptacle and carry these publications through the machine, a pressure roll located adjacent the conveyer to be passed over by the publications in their path of movement, a printing mechanism adapted to be brought 70 into operation at predetermined intervals and to imprint the address upon the publication as it passes over the pressure roll, and means by which said conveyer chain may be adjusted to take publications of various 75 sizes and the printing mechanism and the proximity of the pressure roll with respect to the printing mechanism may be adjusted to imprint the address upon publications of various thicknesses. 80

8. An addressing machine comprising a receptacle in which publications are placed in quantities, conveyers to take the publications singly from the receptacle and to carry these publications through the machine, means to form a label from a continuous strip of material, means to apply the label to the publications as carried through the machine, means forming a part of said conveyers to be adjustable to act 85 upon publications of various sizes and thicknesses and to permit carrying of the publications through the machine in a relation to have the labels affixed at any desired point, printing mechanism to print upon the 90 labels as applied to the publications, means to carry the machine through the successive steps of the operation, and means to form a positive stop for the label affixing and printing mechanism when not in operation. 95

9. An addressing machine comprising a table, a frame on which said table is mounted, carrying means by which publications are moved over the table, a printing mechanism mounted above said table at a point 100 to imprint an address upon each of said publications in its path of travel across the table, said carrying means so constructed that publications of various sizes may be carried in the operative relation and handled to have the address imprinted thereon at any desired point, means to adjust the proximate positioning of the table with respect to the printing mechanism, power 105 means to transmit motion to said carrying means, and means mounted on said carrying means to bring said printing mechanism into operation in the proper intervals and to be adjustable to suit the varying conditions of operation. 110

10. An addressing machine comprising a table, means by which the publications are moved over the table, a printing mechanism mounted at a point to imprint an address upon each of said publications in its path 115 of travel across the table, power means to transmit motion to said carrying means, a power connection to bring said printing mechanism into operation in the proper intervals, said carrying means and power- 120 125

transmitting means so arranged that publications of various sizes can be operated upon, and means to regulate the disposition of the table with respect to the printing mechanism to permit the adaptation of the machine to address publications of various thicknesses and to accomplish the proper printing action in each connection.

11. An addressing machine comprising a supporting frame, conveyers mounted on the frame to carry publications singly through the machine, said conveyers comprising chains having stops positioned thereon at spaced-apart intervals, a printing mechanism located to imprint an address upon each of the publications in its course of travel through the machine, gear connections by which said printing mechanism is operated, power means from which the conveyers are driven, a sprocket chain connected to derive power from the power means through the conveyers, and rack teeth provided on said sprocket chain to engage and mesh with the teeth of the geared connection to the printing mechanism to cause an operation thereof at the proper intervals.

12. An addressing machine comprising a supporting frame, conveyers mounted on the frame to carry publications singly through the machine, said conveyers comprising chains having stops positioned thereon at spaced-apart intervals, a printing mechanism located to imprint an address upon each of the publications in its course of travel through the machine, gear connections by which said printing mechanism is operated, power means from which the conveyers are driven, a sprocket chain connected to derive power from the power means through the conveyers, rack teeth provided on said sprocket chain to engage and mesh with the teeth of the geared connection to the printing mechanism to cause an operation thereof at the proper intervals, and means to positively stop and to maintain the printing mechanism in the proper relation after the rack teeth on said sprocket chain have passed from mesh with said gear wheel.

13. An addressing machine comprising a receptacle in which publications are placed in quantities, a table adjustably disposed to extend the entire length of the machine, conveyers comprising chains provided with stops thereon mounted to take the publications singly from the receptacle and convey these publications along the length of the table, power-transmission means by which the conveyers are caused to be constantly driven during the operation of the machine, means located adjacent the receptacle to sever a label from a continuous strip and to apply an adhesive to said label and attach the label to the publication, printing means located along the table beyond the dis-

position of the label affixing mechanism to imprint an address upon said label, a sprocket chain mounted to derive power from the means transmitting power to the conveyers, gear operating mechanism for said printing means and said label affixing means, and gear teeth carried by certain of the links of said sprocket chain to mesh with said gear connection and to operate the parts.

14. An addressing machine comprising a receptacle in which publications are placed in quantities, a table adjustably disposed to extend the entire length of the machine, conveyers comprising chains provided with stops thereon mounted to take the publications singly from the receptacle and convey these publications along the length of the table, power transmission means by which carrying movement is given to said conveyer chains, means located adjacent the receptacle to sever a label from a continuous strip and to apply an adhesive to said label and attach the label to the publication, printing means located along the table beyond the disposition of the label affixing mechanism to imprint an address upon said label, a drive sprocket chain mounted to derive power from the means transmitting power to the conveyers, gear operating mechanism for said printing means and said label affixing means, gear teeth carried by certain of the links of said drive sprocket chain to mesh with said gear connection to operate the mechanism as hereinbefore set forth, and means to hold the label and printing mechanism in the position in which they are stopped subsequent to the operation and prior to the next operation.

15. An addressing machine comprising a receptacle in which publications are placed in quantities, means to take the publications singly from the receptacle, means to receive the publications as taken from the receptacle and to convey each publication through the machine and cause the discharge therefrom, means to apply a label to each of said publications in its course of travel through the machine, means to imprint an address upon the labels, power means to maintain the operation of the conveying mechanism constant, and mechanism arranged to automatically bring the label applying and printing mechanism into operation at the proper intervals.

16. An addressing machine comprising a supporting frame, a receptacle mounted on the frame in which publications are placed in quantities, conveyer chains mounted on the frame, means by which the publications are taken singly from the receptacle and deposited on said conveyer chains to be carried through the machine, means carried by the frame to affix a label to each of said publications in its course of travel through the machine, printing mechanism to imprint

the address upon said labels, and power means to automatically carry the machine through successive operations.

17. An addressing machine comprising a frame having a table supported thereby, a receptacle in which publications are placed in quantities mounted above said table, conveyors comprising chains provided with stops thereon mounted adjacent the table 10 top, power-transmission means connected to give proper actuating movement to said conveyors, means to take the publications singly from the receptacle and deposit these publications upon the table in a position to be 15 taken by the conveyors, means located adjacent the receptacle to sever a label from a continuous strip and to apply an adhesive to said labels and attach the label to the

publications, printing means located along the table beyond the disposition of the label affixing mechanism to imprint an address upon said label, a sprocket chain mounted to derive power from the means transmitting power to the conveyors, gear operated mechanisms for said printing means, gear wheels mounted to drive said label affixing means, and gear teeth carried by certain of the links of said sprocket chain to mesh with the gear wheels and to operate the parts in the proper intervals. 20 25 30

In testimony whereof I affix my signature in presence of two witnesses.
